CLAIM

The ornamental design for an aerial storage unit for fiber optic cable, as shown and described.

DESCRIPTION

FIG. 1 is an enlarged perspective view of an aerial storage unit for fiber optic cable showing my new design;

FIG. 2 is a top plan view thereof;

FIG. 3 is a bottom plan view thereof;

FIG. 4 is an elevation view of one side thereof, the opposite side being a mirror image;

FIG. 5 is an elevation view of the right end thereof; and,

FIG. 6 is an elevation view of the left end thereof.
